FUEL ECONOMIZER

Gene J. Judd and Charles A. Morgan,
Indianapolis, Ind.

Application January 24, 1935, Serial No. 3,350

6 Claims. (Cl. 122—379)

This invention relates to apparatus for utilizing the heat of flue gases escaping from a furnace. A primary object of the invention is to provide a structure through which flue gases may travel and be transferred to some heating medium such as water capable of being used in an auxiliary heat transfer system. A further primary object of the invention is to provide such apparatus in a very simple, durable, and efficient form which will provide for the greatest transfer of heat from such gases without setting up a cooling effect upon non-flow of the heated gases through the device.

A still further primary object of the invention is to provide means in the heat economizing apparatus which would permit an expansion of the heated flue gases within the device to permit them to rise above the ordinary straight line passage of the gases between the inlet and outlet gas conductors.

A still further important object of the invention is to provide very simple and efficient means for cleaning the exterior surfaces of the coils or pipes containing the water being heated by the flue gases. These and other objects and advantages of the invention including the new and novel assembly of the various elements as defined by the claims, will become apparent to those skilled in the art and reference is made to the accompanying drawings in describing one particular form of our invention as now best known to us.

Referring to the drawings, Fig. 1 is a side elevation in a more or less diagrammatic form of an installation embodying our invention.

Fig. 2, an end elevation of the economizer unit with the end wall broken away,

Fig. 3, a detail in horizontal section on the line 3—3 in Fig. 1,

Fig. 4, a horizontal transverse section on the line 4—4 in Fig. 1;

Fig. 5, a detail in side elevation of the scraping mechanism,

Fig. 6, a detail in horizontal transverse section of the water tube support, and

Fig. 7, an end view of the scraper.

Like characters of reference indicate like parts throughout the several views in the drawings.

Referring to Fig. 1, the economizer unit, generally designated by the numeral 10, is mounted upon a supporting base or frame 11 so as to have the inlet collar 12 at the proper elevation above the floor to receive the smoke pipe 13 extending from the heating furnace 14, herein shown as a hot air furnace, although the invention is not

to be considered as being limited to the primary source of flue gases as coming from a hot air furnace.

Flue gases are conducted from the economizer 10 through the pipe 15 and thence on into the stack (not shown). It is important to have the smoke pipes 13 and 15 entering and leaving, respectively, the economizer 10 at the same elevation as will be discussed more fully hereinbelow.

The economizer unit itself will now be described. We provide a base 16 of metal, cast iron being suitable. The base is preferably made to be narrower in width than its length and has a number of transversely disposed bars 17 resting thereon. Each of these bars 17 has a foot 18, Fig. 6, at each end, downturned to rest on the base 16 so as to leave an opening between the base and the bar.

We place a number of tube sections 19 in parallel relation on these bars 17 to extend longitudinally of the base 16. Each section is spaced from the adjacent section, and is composed of a series of tubes 20 spaced one from the other. It is particularly desired that each of these tubes within each section have flat surfaces extending throughout their vertical lengths rather than round surfaces. In the form herein shown, these tubes 20 are rectangular in shape thus presenting four exterior flat faces. The sections are interconnected one with the other by nipples 21 across their lower ends adjacent one end of the base 16, such end being the left hand end as viewed in Fig. 1 or that end toward the flue gas intake of the economizer. The sections are similarly interconnected by nipples 22 at their upper and opposite ends as indicated in Fig. 2.

We provide a housing which rests on the base 16 to completely enclose the tubular sections 19 40 assembled as above indicated. This housing is a box-like structure spaced from the sections somewhat and securely held in place by the bolts 23 extending through ears 24 on the housing and through the base 16. In the form herein shown, we have provided the housing with a double wall on its two sides and top so as to receive water therein to form a water jacket to further absorb heat from flue gases. The end walls are preferably left single on account of 45 being easier to assemble in that condition.

As above indicated the flue gas intake collar 12 is located on the end wall of the economizer toward the base 16 at that end where the sections 19 are interconnected by the nipples 21 on their 55

lower sides. The outlet pipe 15 preferably leaves the housing from a side but adjacent the opposite end as indicated in Fig. 4, the pipe 15 being received by the collar 25. Both the collars 12 and 5 25 are at the same elevation above the base 16. Furthermore the collars are carried by the housing in an extended position so as to form as indicated in Fig. 2 a chamber 26 between the collars and the sections 19 to give ample room for flue 10 gas travel without having the sections 19 interfering therewith.

It is necessary, in order to secure the greatest exchange of heat from the flue gases entering the economizer 10 to keep the exterior walls of the 15 tubes 20 in the sections 19 clean and free of coal soot. To this end, we provide a scraping mechanism which will now be described. We form a framework 27 which will just fit within the housing on the outside of the sections 19 so that it 20 may be raised and lowered thereabout. We then fix to this frame 27, channel bars 28 to extend longitudinally of the sections 19 to have the upturned legs thereof in frictional contact with the opposing walls of the tubes within those sections. There is also a channel bar 28 on the outermost sides of the outer sections 19 to travel 25 between those outer sections and the wall of the housing. We also mount a plurality of channel bars 29 to extend transversely across the bars 28, 30 one such bar 29 being between each of the opposing faces of the tubes in the sections and also a bar on each extreme outer end of the sections between them and the end walls of the housing.

These channel bars 28 and 29 are preferably 35 formed to have their legs extending angularly outwardly against the respective tubular walls so as to exert a shearing action therealong tending to cut and shave off the accumulation of scale and soot along the tubular walls. By reason of the fact that the tubular walls present flat faces, it is to be noted that all of the area of those faces may be readily scraped by the projecting edges of the channel bars 28 and 29 as the frame 27 may be raised within the housing.

45 In order to reciprocate the frame 27 to effect the scraping of the tubes, we attach a shaft 30, here shown as centrally of the frame 27 and cause it to extend downwardly through the floor 16 through a stuffing box 31 so that the shaft 30 50 may be raised and lowered therethrough and a gas tight fit maintained therearound. The lower end of the shaft 30 is fitted with a grooved wheel 32 which rides over inwardly turned flanges 33 and 34 of the respective T irons 35 and 36 which 55 are fitted to the under side of the base or floor 16 on the bracket 37 to hang downwardly therefrom.

The axle 38 about which the wheel 32 is 60 mounted on the shaft 30 extends outwardly on both sides of the mounting bracket 39. One end of the extending axle 38 enters a slot 40 in the end of a lever 41 which is rockably mounted on the supporting frame 11 to have a foot pedal 42 extending therefrom. By pushing downwardly 65 on the pedal 42, the shaft 30 may be raised so as to lift the scraper frame 27 to cause the channel members 28 and 29 to scrape the tubes as the members are carried upwardly thereby. The weight of these members and their frame is sufficient to cause them to drop downwardly when pressure is removed from the pedal 42. In order to prevent damage by dropping of the channels under their own weight, we provide a counter-balance 43, Fig. 2, which is attached to the 70 75 end of a cable 44 passing upwardly over a pulley

45 secured to the floor 16 and thence downwardly to an end of the axle 38.

In the form herein shown, where the sections 19 are designed to carry water to which the heat is to be transferred from the flue gases, we provide an inlet pipe 46 which enters the lower end of one of the sections 19 at the inlet end and base thereof. An outlet pipe 47 leads from the top of one of the sections 19 and is carried upwardly. The pipes 46 and 47 are suitably interconnected with a heat radiating member 48, here shown as a radiator of the common and well known type, so that as the water in the sections 19 may become heated, a circulation of the water will be had through the radiator 48.

In operation, whenever there is a fire in the furnace 14, flue gases will escape from that furnace through the pipe 13 and enter within the housing of the economizer 10 to pass about and around the various tubes of the sections 19. The 20 gases may escape through the outlet pipe 15 which, as above indicated, is maintained at the same level as that of the intake pipe 13. By reason of the arrangement of these pipes 13 and 15, the flue gases immediately upon entering with- 25 in the collar 12 may expand and rise upwardly within the housing of the economizer and heat the upper portion of the surface without any direct draft through that upper part. The draft is maintained across the under ends of the sec- 30 tions 19 so that the difficulty sometimes encountered heretofore in economizers is eliminated by preventing the cooling off of the tubes in the sections 19 by passage of air through the device which has not been heated or which passes so 35 rapidly as not to give up a sufficient amount of the heat to heat the water within the tubes.

In referring again to the scraping mechanism, it is to be noted that each of the channel bars 28 are cut through between webs at the sides of the respective tube faces so that the soot and scale scraped off may drop through the openings 49 and down onto the floor 16. Likewise the transverse channels 29 are cut through to leave openings 50 on the other sides of the tube faces 40 to provide similar discharge openings. A clean- 45 out door 51 is provided in one end of the economizer wall so that the door may be removed and the accumulation on the floor 16 scraped along under the bars 17 to discharge into some suit- 50 able receptacle (not shown) over the lip 52.

While we have herein shown our invention in the best form as now known to us, it is obvious that structural changes may be made without departing from the spirit of the invention and we 55 therefore do not desire to be limited to that precise form beyond the limitations as may be imposed by the following claims.

We claim:

1. In a flue gas heat transfer device, a plurality of vertically disposed interconnected heat receiving tubes having plane faces angularly disposed one to the other, a housing surrounding the tubes in spaced relation, a scraper unit comprising upturned scraping members extending 60 between said tubes to have edges thereof in parallel relation to and in contact with said tube faces, and means for moving said members upwardly along said faces, said housing having flue 65 gas intake and outlet openings removed one from 70 the other and both at the same elevation near the base of said tubes.

2. In a flue gas heat transfer device, a plurality of vertically disposed interconnected heat receiving tubes having plane faces angularly dis- 75

posed one to the other, a housing surrounding the tubes in spaced relation, a scraper unit comprising upturned scraping members extending between said tubes to have edges thereof in parallel relation to and in contact with said tube faces, and means for moving said members upwardly along said faces, said means comprising a shaft connected with said members and extending from the housing, and an operating lever 10 interengaging said shaft.

3. For utilizing heat from flue gases escaping from a furnace, an economizer to be placed in the smoke-pipe of the furnace comprising, a base, a plurality of tubular sections, means for supporting and spacing the sections from the base in spaced apart parallel relation, said sections being interconnected across their lower and top ends, the tubes in each section being formed to have vertically disposed plane faces, scraping members extending horizontally between the tubes to have scraping edges parallel to all of the tube faces, and means for moving said members along said tubes.

4. In an economizer, a plurality of vertically disposed tubes each having a plurality of plane faces, and a tube scraping unit comprising horizontally disposed members arranged to extend between and around the tubes parallel with said faces, each of said members having edges directed toward and in contact with respective tube faces, and each of said members being provided with openings therethrough adjacent each of said faces.

5. In an economizer, a plurality of vertically

disposed tubes each having a plurality of plane faces, and a tube scraping unit comprising horizontally disposed members arranged to extend between and around the tubes parallel with said faces, each of said members having edges directed toward and in contact with respective tube faces, and each of said members being provided with openings therethrough adjacent each of said faces, a floor supporting said tubes in spaced relation therefrom, a vertical shaft connecting 10 with said members and slidably passing through said floor, guide means maintaining said shaft in alignment, and an operating lever interconnected with said shaft.

6. In an economizer, a plurality of vertically disposed tubes each having a plurality of plane faces, and a tube scraping unit comprising horizontally disposed members arranged to extend between and around the tubes parallel with said faces, each of said members having edges directed toward and in contact with respective tube faces, and each of said members being provided with openings therethrough adjacent each of said faces, a floor supporting said tubes thereabove, and a housing surrounding the tubes forming a box-like enclosure over said floor, said housing having flue gas inlet and outlet openings in removed walls thereof at the same elevation, and said tubes having an inlet pipe at their lower ends near said housing inlet opening and having an outlet pipe at their upper ends above said housing outlet opening.
